UNITED STATES PATENT OFFICE.

HARRY A. MURRAY AND WILLIAM T. DORMAN, OF HOUSTON, TEXAS, ASSIGNEES OF
ONE-THIRD TO CLAUDE POLLARD, OF HOUSTON, TEXAS.

INTERNAL-COMBUSTION ENGINE.

1,220,380.

Specification of Letters Patent. Patented Mar. 27, 1917.

Application filed October 15, 1914. Serial No. 266,843.

To all whom it may concern:

Be it known that we, HARRY A. MURRAY and WILLIAM T. DORMAN, citizens of the United States, and residents of Houston, in the county of Harris and State of Texas, have invented certain new and useful Improvements in Internal-Combustion Engines.

Our invention has for its object to improve that class of explosive engines especially adapted to be used in connection with motor vehicles and all internal combustion gas engines.

The primary object of our invention is to provide an internal combustion engine using a volatile hydro-carbon or similar fuel, with an attachment insuring absolute freedom from carbon deposits in the cylinder, resulting in a more complete combustion of the explosive medium.

Another object is to provide an internal combustion engine with an attachment insuring an efficient mixture of gas and vapor, resulting in a properly balanced explosive mixture, insuring economy in fuel consumption, while further keeping the engine cooler than is possible under ordinary conditions.

With these and other objects in view the present invention consists in the combination and arrangement of parts as will be hereinafter more fully described and finally pointed out in the appended claims, it being further understood that changes in the specific structure shown and described may be made within the scope of the claims without departing from the spirit of the invention.

In the accompanying drawing we have shown a broken portion of a conventionally constructed internal combustion gasolene engine cylinder provided with an attachment embodying our invention.

In our present invention we provide an attachment the use of which eliminates the deposit of carbon upon the cylinder walls, as well as on the face of valves and seats, thus eliminating the blowing by piston packing rings.

We further effect a more efficient and perfect gasolene mixture by tapping into the top of the water jacket or other convenient source. The water is not forced by a pump but gravitates and is drawn by a vacuum instead. Our system gives a mixture in the carburetor to each cylinder used, and

supplied by a distributor conventionally used on any type of engine.

The use of our attachment insures an explosive mixture which explodes more readily and with greater efficiency than is possible under ordinary conditions. Further should the amount of water to form the vapor be in excess of the requirement, the surplus can be readily detected, though if not noticed at once, will do no damage to the working parts of the engine. This we accomplish in running a copper coil with regulating valves around the exhaust pipe a sufficient number of times to heat the water causing a vapor, the mixture of which with the explosive gas permits the use of a very low grade of gasolene or solar oils.

In the drawings A represents the water jacket surrounding the cylinder, and B the valve chamber.

Entering the top 9 of the water jacket, and communicating therewith, is the valve 4 operated by means of the stem 2.

Extending from the valve 4 is the heating pipe 6, preferably made of copper which is coiled several times about the exhaust pipe 7, finally being secured to the valve 8. Secured to the valve 8 is the pipe section 5 which leads into the intake pipe 3. The valve 8 is operated by means of the valve 10 stem 10. This pipe 3, it is of course understood, leads from the carburetor. In the drawings the pipe 12 leads from the radiator, while the stems 13 and 14 communicate, respectively, with the intake and exhaust valves.

It is of course understood that the flow of water is from the water jacket into the intake pipe 3, as is indicated by the arrows. The water escapes first through the valve 4, then flows through the coil pipe sections, and then through the valve 8, and finally through the pipe section 5 into the intake pipe 3, as disclosed.

Our attachment is simple and inexpensive in construction, and both durable and efficient in operation and insures the interior of a cylinder, as well as the exposed valves and valve seats remaining free from carbon deposits.

Having thus described our said invention what we claim as new and desire to secure by Letters Patent is:

1. The combination of the cylinder of an internal combustion engine having a water

- jacket provided with means for supplying water thereto, of an intake pipe having a horizontal portion and communicating with the cylinder, a vertically disposed exhaust pipe communicating with the cylinder, a pipe communicating at one end with the water jacket and coiled around the vertical exhaust pipe and communicating at its opposite end with the under side of the horizontal portion of the intake pipe, said pipe at all times containing a supply of water, whereby water in the coil is heated and flows by gravity and accumulates in the bottom of the longitudinal portions of the pipe from whence it is drawn into the cylinder and vaporized with the gas by the suction of the piston, and a manually controlled valve for controlling the water passing through the pipe.
2. The combination of the cylinder of an internal combustion engine having a water jacket provided with means for supplying

water thereto, of an intake pipe having a longitudinal portion and communicating with the cylinder, an exhaust pipe communicating with the cylinder, a pipe communicating at one end with the water jacket and coiled adjacent the exhaust pipe and communicating at its opposite end with the horizontal portion of the inlet pipe, said pipe at all times containing a supply of water, whereby water in the coil is heated and flows into and accumulates in the horizontal portion of the intake pipe to be drawn into the cylinder and vaporized with the gas by the suction of the piston.

In testimony whereof we affix our signatures, in the presence of two witnesses.

HARRY A. MURRAY.
WILLIAM T. DORMAN.
